(No Model.)

S. C. PARSONS.
WATER FILTER.

No. 591,006.

Patented Oct. 5, 1897.

UNITED STATES PATENT OFFICE.

SAMUEL C. PARSONS, OF PHILADELPHIA, PENNSYLVANIA, ASSIGNOR OF
TWO-THIRDS TO THOMAS L. MATTSON, OF SAME PLACE.

WATER-FILTER.

SPECIFICATION forming part of Letters Patent No. 591,006, dated October 5, 1897.

Application filed October 31, 1896. Serial No. 610,679. (No model.)

To all whom it may concern:

Be it known that I, SAMUEL C. PARSONS, a citizen of the United States, residing at Philadelphia, in the county of Philadelphia and State of Pennsylvania, have invented a certain new and useful Improvement in Water-Filters, of which the following is a specification.

My invention relates to a new and useful improvement in water-filters, and has for its object to so construct and arrange a device of this description as to bring about a perfect filtration of the water passing therethrough, as of the coarser foreign substances which may be held in suspension, and finally to clarify the water by removing therefrom all discolored agents as well as chemical impurities.

A further object of my invention is to provide means whereby a primary filter will automatically be flushed, so as to relieve coarser particles which may have collected thereon and convey the same to a drain-pipe or other suitable receptacle.

With these ends in view this invention consists in the details of construction and combination of elements hereinafter set forth, and then specifically designated by the claims.

In order that those skilled in the art to which this invention appertains may understand how to make and use the same, the construction and operation will now be described in detail, referring to the accompanying drawing, which is a sectional view of the primary and secondary filter, the several pipes leading to and from the same being in elevation.

In carrying out my invention I provide a cylindrical casing A, which serves as the primary filter and is divided into three compartments by the perforated diaphragms B and C, each of which has a wire screen D of fine mesh, so as to prevent the material placed within the several compartments from passing from one compartment to another. The bottom of the casing is concaved and a perforated diaphragm E rests upon the upper edges of this bottom, so as to form a space therebelow for the outflowing of the water passing through the filter. The compartment next above the diaphragm E is filled with charcoal, as indicated at F, and gravel

G is placed upon the diaphragm B to fill the next compartment.

The superior compartment of the casing has fitted therein a plunger I, which is provided with the flanges J, so as to form a receptacle for the sand or gravel K, and over this sand is secured a screen L. The rod M projects upward from the plunger through the gland in the top of the casing and has coiled thereabout a spring N, said spring having a tendency to elevate the plunger within its compartment, for the purpose hereinafter set forth.

The lever O is pivoted at P and to a supporting-arm, and is also pivoted to the plunger-rod at one end and to the link Q at the other end, which latter in turn is pivoted to the valve-stem R, said stem passing through the gland S and having attached to its lower end a valve T, normally held upon its seat by the spring U in conjunction with the spring N.

The valve-casing V communicates with the superior chamber with the casing A through the nipple W, and a pipe X leads from said valve-casing to the drain. Y is the inlet-pipe, which leads to the upper compartment of the casing A, and the passage therethrough is controlled by a valve Z. From the lower end of the casing A passes the outlet-pipe a, in which is also located the valve b for the regulation of the flow through said pipe, and this pipe is connected by the vertical branch c and horizontal pipe d to the secondary filter e, consisting of a cylindrical casing similar in all respects to casing A, and the pipe d has located therein a valve f.

Within the casing e are located the perforated diaphragms g, h, and i for dividing said casing into compartments, the upper one of which is left empty, while the one next below the diaphragm g is filled with silica, as indicated at j, and the bottom compartment is filled with charcoal, as indicated at l, the diaphragm i serving to support this charcoal and leave a free space upon the conveyed bottom of the secondary filter for the ready outflow of the water passing therethrough. This water is conveyed from the casing by the pipe m and the pipe n, in which is located a valve o, through which said water may flow to the location where it is to be used.

Just above the diaphragm *g* the pipe *p* enters the secondary filter, and this pipe may lead to the drain and is supplied with a valve *q* for controlling an outflow through this pipe.

5 The valves *r* and *s* are so located as to permit the reversal of the water-flow to the primary and secondary filter, as will be next explained.

From this description the operation of my invention will be obviously as follows: The valve *Z* having opened water will flow from the supply-pipe *t* in the direction of the arrow through the pipe *Y* to the casing *A* above the plunger *I*, and so long as the perforations of this plunger and the meshes of the screen *L* are unclogged the water will pass through said plunger and thereafter percolate through the gravel *G*, diaphragm *B*, charcoal *F*, and from thence through the outlet-pipe *a*; but 20 when the plunger has become clogged by the accumulation of foreign matter thereon the pressure of the inflowing water will be exerted upon its upper surface to overcome the action of the springs *N* and *U*, thereby forcing said plunger downward below a nipple *W* and at the same time lifting the valve *T* from off its seat, so that the inflowing water may 25 pass through said nipple to the valve-easing and from thence through the pipe *X* to the drain. Now so long as the plunger remains clogged the pressure of the water will hold it in this lowered position and the flushing thereof will continue until the impurities held thereon have been freed and conveyed 30 to the drain. After this has been accomplished the water will again pass through the plunger, thus relieving the upper side thereof of the plunger, when said plunger will be again elevated above the level of the nipple 35 pipe *W*, the action of the springs *N* and *U*.

When the filters are normally in operation the valves *r* and *s* are closed, so that the water flowing through the pipe *a* passes through the branch *c* and pipe *d* to the superior compartment of the secondary filter, 45 from whence it is caused to percolate through the silica *j* and charcoal *l* before gaining access to the pipe *n*, which serves to convey it to the point of use. The passing of the water through this secondary filter, after having 50 been previously relieved of the impurities held in mechanical suspension therein, will relieve it of soluble salts or other chemical impurities, as well as producing clarification, 55 so that when leaving the secondary filter it will be absolutely mechanically pure.

To flush the secondary filter, the valves *f* and *b* are closed, while the valves *r*, *s*, and *q* are opened, thus permitting the water from 60 the supply-pipe *t* to pass in the reverse direction of the arrow marked next adjacent the branch *c*, through the valve *s*, a pipe *m*, to the bottom of the secondary filter, from whence it will flow upward, removing the accumulated 65 impurities from the charcoal and silica, and pass to the drain through the pipe *p*. The filtering material of the primary filter may

also be flushed by closing the valve *Z*, opening the valves *r* and *b*, and depressing the plunger by force exerted upon its rod below the level of the nipple *W*, thus permitting the water to flow in the reverse direction of the arrow marked next adjacent the pipe *a* to the lower portion of the casing *A*, and from thence upward through the filtering material 75 and plunger, and finally to be drained through the nipple *W*, valve-easing *V*, and pipe *X*.

One of the principal advantages of my improvement is that it cannot become clogged by the accumulation of impurities from the water, since these impurities are automatically flushed from the primary filter, thereby permitting an almost continuous flow of water at nearly the pressure maintained in the supply-pipe *t*, and upon this fact depends the 85 value of my improvement in connection with the feeding of boilers and the like, since the foreign substances contained within the water are detrimental to a boiler.

While my improvement is specially adapted 90 for such uses, it is equally adapted for use in connection with the service-pipe of dwellings, hotels, and large buildings, since the water passing therethrough will at all times be mechanically and substantially chemically 95 pure, as well as clarified, thus especially fitting it for the use to which such water is put and from a sanitary standpoint greatly enhancing the value of said water.

Having thus fully described my invention, 100 what I claim as new and useful is—

1. A filter comprising a casing, a filtering agent located therein, a plunger adapted to slide within said casing, said plunger having a rod leading therefrom, means for maintaining the plunger in a normally-elevated position, an inlet-pipe entering the casing above the plunger, an outlet-pipe leading from the casing below the normal position of the plunger, and a valve so connected with the plunger as to be lifted from off its seat when the plunger is forced outward, as specified. 105

2. In a filter, a casing, a filtering agent located therein, a plunger fitted in the upper portion of said casing so as to slide, said plunger being perforated, a rod leading from the plunger, a spring for holding said plunger in a normal position, a valve connected with the plunger by suitable leverage, a cylinder in which said valve is located, an inlet-pipe leading to the casing above the plunger, and an outlet-pipe leading from the casing below the normal position of the plunger and communicating with the cylinder, substantially as and for the purpose set forth. 115

3. In combination, a casing, partitions *B* and *C* for dividing the interior of said casing into three compartments, filtering material located in the two inferior compartments, a plunger fitted to slide in the upper compartment, a rod leading from said plunger, a spring for elevating the rod and plunger, a valve-cylinder *V*, a pipe connecting the valve-cylinder to the casing, a pipe leading from 125

said cylinder, a valve adapted to close the passage to the pipe X, a suitable connection between the valve and the plunger-rod, and a pipe a leading from the casing below the filtering agents, substantially as and for the purpose set forth.

4. The herein-described combination of a primary filter and a secondary filter, the primary filter consisting of a casing divided into three compartments by the partitions B and C both of which are perforated, filtering agents located in the two inferior compartments, a plunger fitted to slide within the upper compartment, a rod M connected to said plunger, a spring N coiled about said rod, a lever O pivoted at one end to the rod, a valve-stem connected to the opposite end of said lever, a valve carried by said stem, a cylinder in which said valve is located, an inlet-pipe leading to the casing above the plunger, a pipe W leading from the casing to the cylinder, and a pipe X leading from the cylinder to a suitable drain, and a pipe a arranged to connect the primary and secondary filters, substantially as and for the purpose set forth.

5. In combination with a filter of the character described, an outlet-pipe located near the top of the filter, a spring-pressed porous

plunger held normally above the pipe, a valve 30 controlling the outlet-pipe and adapted to be raised out of its seat when the plunger is depressed below the outlet-opening, substantially as described.

6. A filter having a porous plunger arranged 35 therein, an outlet-pipe, means for holding the plunger normally above the pipe, said plunger, when clogged being adapted to be depressed below the opening by the pressure of the water, substantially as described. 40

7. In a device of the character described, a casing, a plunger therein said plunger consisting of a perforated receptacle, a filtering agent provided in said receptacle and a screen secured over the filter agent, a pipe leading 45 from said receptacle and a spring for normally holding said plunger above the pipe, the plunger when clogged being adapted to be depressed below the outlet-opening by the pressure of the water overcoming the action 50 of the spring substantially as described.

In testimony whereof I have hereunto affixed my signature in the presence of two subscribing witnesses.
